(57) **ABSTRACT**

A glove is provided that includes a body configured to engage a hand and a plurality of finger sheaths configured to cover fingers of the hand. The glove also has an electrically conductive ink disposed at least at the tip of at least one of the finger sheaths to interact with a proximity sensor, such as a capacitive sensor.

GLOVE HAVING CONDUCTIVE INK AND METHOD OF INTERACTING WITH PROXIMITY SENSOR

FIELD OF THE INVENTION

The present invention generally relates to activation of proximity sensors, and more particularly relates to an enhanced conductivity glove and method of interacting with a proximity sensor, such as a capacitive sensor.

BACKGROUND OF THE INVENTION

Various electronic devices, such as consumer electronic devices, employ touch screen inputs, typically in the form of capacitive touch screen sensors. Additionally, automotive vehicles are being equipped with proximity sensors, such as capacitive sensors, which may be used as switches to control various devices and perform various functions onboard the vehicle. Capacitive switches typically employ one or more proximity sensors to generate a sense activation field and sense changes to the activation field indicative of user activation of the sensor, which is typically caused by a user's finger in close proximity or contact with the sensor. Proximity sensors are typically configured to detect user activation of the sensor based on comparison of the sense activation field to a threshold.

Generally, capacitive sensors sense a touch of the bare hand of a user, such as the fleshy fingertip, due to conductivity of the flesh, which perturbs the activation field. Problems often arise when a user wears protective gloves that cover the hands, such as for work or during cold weather conditions. Many devices employing capacitive sensing technology are generally inoperable for users wearing gloves because the material of the glove typically acts as an electrical insulator that isolates the finger and prevents the detection of the conductivity of the fingertips of the hand. This can become a problem, especially for automotive applications in which users often enter a vehicle during cold conditions and employ the vehicle in a work environment where gloves are advantageously worn by a user. It has been proposed to manufacture conductive material in gloves, however, conventional proposals typically require fabrication of the glove to include the conductive material. It is desirable to provide for a glove and methodology of employing a glove that allows for easy use of capacitive sensors by a user without requiring extensive modification of the glove.

SUMMARY OF THE INVENTION

According to one aspect of the present invention, a glove is provided that includes a body configured to engage a hand and a plurality of finger sheaths configured to cover fingers of the hand. The glove also includes an electrically conductive ink disposed on at least one of the finger sheaths.

According to another aspect of the present invention, a glove is provided that includes a body configured to receive a hand. The glove also includes a plurality of sheaths configured to cover fingers of the hand. The glove further includes an electrically conductive material disposed on at least one of the sheaths, wherein the electrically conductive material is formed by applying a liquid conductive ink to the at least one sheath and drying the conductive ink.

According to a further aspect of the present invention, a method of interacting a proximity sensor with a hand wearing a glove is provided, wherein the glove has finger sheaths that cover fingers of the hand. The method includes

2

the steps of applying a liquid conductive ink to at least one finger sheath and drying the conductive ink. The method also includes the step of moving the finger sheath toward a proximity sensor to activate the proximity sensor with the dried conductive ink.

These and other aspects, objects, and features of the present invention will be understood and appreciated by those skilled in the art upon studying the following specification, claims, and appended drawings.

10

BRIEF DESCRIPTION OF THE DRAWINGS

In the drawings:

FIG. 1 is a perspective view of a glove worn by a user illustrating the step of applying a liquid conductive ink to the tip of a sheath by dipping the glove in the ink, according to one embodiment;

FIG. 2 is a perspective view of the glove illustrating the step of drying the conductive ink such that glove may be used to operate a proximity (e.g., capacitive) sensor;

FIG. 3 is a perspective view of the application of a liquid conductive ink to the tip of a sheath by spraying the liquid conductive ink thereon, according to another embodiment;

FIG. 4 is a flow diagram illustrating a method of applying a conductive ink to a glove and interacting with a proximity sensor therewith, according to one embodiment;

FIG. 5 is a side perspective view illustrating use of the glove with conductive ink to interact with a proximity sensor.

30

DETAILED DESCRIPTION OF THE PREFERRED EMBODIMENTS

As required, detailed embodiments of the present invention are disclosed herein; however, it is to be understood that the disclosed embodiments are merely exemplary of the invention that may be embodied in various and alternative forms. The figures are not necessarily to a detailed design; some schematics may be exaggerated or minimized to show function overview. Therefore, specific structural and functional details disclosed herein are not to be interpreted as limiting, but merely as a representative basis for teaching one skilled in the art to variously employ the present invention.

Referring to FIGS. 1-3, a glove 10 is generally illustrated configured to be worn on a hand 14 of a user, and configured to provide enhanced interaction with a proximity sensor, such as a capacitive sensor. The glove 10 is shown in FIG. 1 during the step of applying a clear or transparent conductive ink to a tip portion of at least one finger sheath of the glove 10, according to one embodiment. The glove 10 generally includes a body configured to cover the hand including the palm and backside of the hand, according to a conventional style glove. The glove 10 also includes a

plurality of finger sheaths 12 configured to individually cover the fingers or digits of the hand. Each sheath has a tip at the proximal end of the sheath 12. At least one of the finger sheaths 12 is configured to have an electrically conductive material in the form of a clear conductive ink applied to at least one of the tips of the finger sheaths 12 such that the glove 10 may advantageously be employed to interact with or operate a proximity sensor, such as a capacitive sensor, with enhanced sensing capability.

As shown in FIG. 1, the glove 12 worn by a user is modified by applying a clear conductive liquid ink to at least the tip portion of at least one of the sheaths 12. This may be achieved by a user wearing the glove 10 on the hand thereof

65

and inserting at least one finger and the tip of the covering sheath 12 into a liquid bath of clear highly transparent conductive ink 22 shown disposed within container 24. It should be appreciated that a user may select from many different types or styles of gloves and may easily modify the electrical conductivity of the glove 10 by applying a clear conductive ink to a sheath portion 12 so as to advantageously provide for an enhanced capacitive sensor operating glove. The container 24 of clear conductive bath 22 may be a small container of liquid conductive ink that may be readily transportable and made available to a user for an initial application to the glove 10 or made available for reapplying an application of conductive ink to the glove 10 to enhance electrical conductivity characteristics of the glove 10 for use with proximity sensors.

Once a sufficient amount of the tip portion of the sheath 12 is coated with the liquid conductive ink, the glove 10 is removed from the bath 22 of container 24 and the liquid conductive ink 22 is allowed to dry as shown in FIG. 2. The conductive ink 22 dries on the glove 10 to form a dried conductive portion 20 which may advantageously be used to provide enhanced operation of or interaction with a proximity sensor, such as a capacitive sensor. Once dried, the ink remains highly transparent. By employing a clear or visibly transparent conductive ink, the color and look of the glove 10 may appear to remain unchanged to the visible eye of a user (human). As a result, different types of gloves employing different materials and colors may be employed and the look of the glove 10 may not visibly appear to be changed due to the application of the clear conductive ink; however, the electrical conductivity characteristics of the glove 10 is enhanced by employing the clear conductive ink to enhance the capacitive sensing characteristic.

Referring to FIG. 3, a glove 10 is shown worn on the hand of a user during application of a clear conductive ink by a spraying technique, according to another embodiment. In this embodiment, a clear conductive ink 22 may be contained within a spray container 26 and may be sprayed onto a desired portion, such as a tip of at least one sheath 12, of the glove 10 as shown. The container 26 may include a pressurized pump sprayer or an aerosol spray container, according to a couple of embodiments. The user may easily carry the spray container 26 and apply a clear conductive ink 22 to the glove 10 as needed to provide enhanced electrically conductivity characteristics to the glove 10 to enable enhanced operation or interaction with proximity sensors or switches. It should be appreciated that the clear conductive ink 22 may be applied to the glove 10 when the glove 10 is worn by a user or the conductive ink 22 may be applied to the glove 10 absent insertion of the hand and finger within the glove 10.

The clear or physically transparent conductive ink 22 may include a commercially available off the shelf conductive ink, such as EL-P ink sold under the brand name Orgacon™, such as EL-P 3000, which is made commercially available by AGFA, according to one example. Orgacon™ EL-P ink is a highly transparent, screen printable conductive ink, based on conductive polymers. The ink includes conductive polymers and a thermoplastic polymer binder. The liquid ink may be applied as a patch or in a desired pattern. The transparent conductive ink 22 may include a commercially available off the shelf conductive ink sold under the brand name Clevios™ P which is commercially available by Heraeus, according to another example. It should be appreciated that other conductive inks may be employed to provide an enhanced electrical conductivity to the glove 10. It should further be appreciated that other techniques for

applying the liquid conductive ink to one or more portions of the glove 10 may be employed.

The transparent conductive ink 22 is applied as a liquid that coats a surface portion of the glove 10 and may soak into the layer or layers of the glove 10. The liquid ink may soak all the way through from the outside to the inside of the glove 10, thereby providing an enhanced conductive path through the glove thickness to the finger of a user. This may be particularly advantageous for use with single electrode capacitive switches which include a proximity sensor such as a capacitive sensor which may use the added conductive path through the glove formed by the conductive ink to provide a ground path to the user. Gloves that are capable of absorbing the liquid ink include cloth gloves, such as cotton, wool, polyester, leather and other liquid permeable materials. By allowing the ink to soak through the glove 10, thicker gloves may be provided with greater conductivity and enhanced sensor operation. It should further be appreciated that the conductive ink could be applied to both the outside surface of the glove and the inside surface, and may be applied using other techniques such as an eye dropper. The viscosity of the conductive ink may vary, depending upon the permeability of the glove so as to realize sufficient permeation of the ink into the glove.

The enhanced electrical conductivity glove 10 achieved with the conductive ink as shown and described herein may be employed to operate proximity sensors, such as capacitive sensors, which generate sense activation fields and sense changes to the activation fields indicative of user activation of the sensors, typically caused by the user's finger in close proximity to or contact with each sensor. With the added electrical conductivity of the conductive ink 22, the gloved finger provides enhanced activation of a proximity sensor. The glove 10 may be operable to interact with a proximity sensor configured as a capacitive sensor, according to one embodiment. The capacitive sensor may function as a capacitive switch comparing the sensed activation field to a threshold. According to other embodiments, the glove 10 may interact with other proximity sensors, such as an inductive sensor or a resistive sensor, wherein the conductive ink provides enhanced interaction with the sense activation field of the proximity sensor.

The glove 10 may be advantageously utilized to operate one or more proximity sensors on an automotive vehicle so as to control one or more devices or perform one or more control functions. For example, proximity sensors may be used as user actuated switches, such as switches for operating devices including powered windows, headlights, windshield wipers, moonroofs or sunroofs, interior lighting, radio and infotainment devices, and various other devices. For automotive applications, proximity sensors may be located in overhead consoles, center consoles, headliners, doors, visors, instrument panel clusters, navigation displays and other areas on the vehicle. Users may advantageously be able to operate the proximity sensors in various temperature conditions including extreme cold conditions where the use of a glove is desirable or necessary. Additionally, work vehicles may be equipped with proximity sensors that interact with the enhanced conductivity glove 10, thereby allowing workers in the vehicle to wear their gloves to operate various sensors onboard the vehicle. The glove 10 may further be used to operate various other proximity sensors, such as capacitive sensors, for other applications. For example, phones, computers, PDAs, games, and other consumer electronic devices may employ proximity sensors, such as capacitive sensors, that may be operated with enhanced performance with the use of the glove 10.

Referring to FIG. 4, a method of enhancing the electrical conductivity of a glove and interacting the glove with a capacitive sensor is illustrated, according to one embodiment. Method 100 includes step 102 of providing a glove. The glove may include any of a variety of types of gloves such as an off the shelf commercially available glove. The glove may be made of electrically non-conductive material, such as leather, cotton, rubber and other materials, and may have any desired thickness and insulation properties. At step 104, method 100 applies a clear conductive ink to at least one finger sheath, particularly to the tip portion where a finger of the hand is adapted to be present when the glove is worn. The clear conductive ink may be applied at a sufficient amount for a sufficient time period to allow the ink to soak into the glove, for a liquid permeable glove. Next, at step 106, method 100 dries the conductive ink that was applied to the glove such that the ink cures. Once dried, the ink may form a conductive path on the surface of the glove and extending through the layers of the glove so as to provide a conductive path to the finger of a user wearing the glove. Once the ink is dried, method 100 proceeds to step 108 to allow a user to wear the glove to cover the user's fingers and hand. With the glove worn on the hand, a user may proceed to step 110 to use the glove to activate one or more proximity sensors or switches. The interaction of the dried conductive ink of the glove provides for enhanced electric conductivity which provides for enhanced detection or interaction with proximity sensors.

One example of the glove 10 having a conductive ink 20 applied to a tip of the sheath 12 and used to interact with a proximity sensor is illustrated in FIG. 5. A user wearing the glove 10 may simply swipe through a sense activation field 32 provided by a capacitive sensor 30 as shown. The finger, glove, and the enhanced conductive ink 20 provides a disturbance to the sense activation field 32 which is detected by the sensor 30 and used to determine activation of the proximity sensor by the user, which may allow for enhanced control of one or more devices or functions.

Accordingly, the glove 10 having a clear conductive ink applied thereto advantageously allows for many forms of gloves to be employed to provide enhanced interaction with a capacitive sensor. The method of interacting with the glove 10 advantageously allows users to provide enhanced capacitive sensing operation without the need to substantially modify the glove 10 or require that a user buy a special manufactured glove, or to remove the glove. This results in enhanced use of the capacitive sensors for users that wear gloves.

It is to be understood that variations and modifications can be made on the aforementioned structure without departing from the concepts of the present invention, and further it is to be understood that such concepts are intended to be covered by the following claims unless these claims by their language expressly state otherwise.

We claim:

1. A glove comprising:
a body configured to engage a hand;
a plurality of finger sheaths configured to cover fingers of the hand; and
an electrically conductive ink disposed on at least one of the finger sheaths, wherein the electrically conductive ink penetrates through and extends from an outside

surface to an innermost surface of the glove to provide a conductive ground path through a thickness of the glove configured to ground a proximity sensor to a finger of the hand.

2. The glove of claim 1, wherein the electrically conductive ink comprises a visibly clear conductive ink.
3. The glove of claim 2, wherein the clear conductive ink comprises a conductive polymer.
4. The glove of claim 1, wherein the electrically conductive ink is disposed on a tip of the at least one finger sheath.
5. The glove of claim 1, wherein the conductive ink is applied to the glove by dipping at least a portion of the at least one finger sheath in a liquid conductive ink.
6. The glove of claim 1, wherein the conductive ink is applied to the glove by spraying the liquid conductive ink onto the at least one finger sheath.
7. The glove of claim 1, wherein the conductive ink is applied on the outer surface of the at least one finger sheath.
8. The glove of claim 1, wherein the glove is adapted to operate a capacitive sensor in an automotive vehicle.
9. A glove comprising:
a body configured to receive a hand;
a plurality of finger sheaths configured to cover fingers of the hand; and
an electrically conductive material formed on at least one of the finger sheaths by applying a liquid conductive ink to the at least one finger sheath and drying the conductive ink, wherein the electrically conductive ink penetrates through and extends from an outside surface to an innermost surface of the glove to provide a conductive ground path through a thickness of the glove configured to ground a proximity sensor to a finger of the hand.
10. The glove of claim 9, wherein the liquid conductive ink is applied by dipping at least a portion of the at least one finger sheath in liquid ink.
11. The glove of claim 9, wherein the liquid conductive ink is applied by spraying the liquid conductive ink onto the at least one finger sheath.
12. The glove of claim 9, wherein the liquid conductive ink comprises a conductive polymer.
13. The glove of claim 9, wherein the electrically conductive ink is applied to a top of the at least one finger sheath.
14. A glove comprising:
a body configured to engage and cover a hand including fingers of the hand; and
an electrically conductive ink disposed on the body, wherein the electrically conductive ink penetrates through and extends from an outside surface to an innermost surface of the glove to provide a conductive ground path through a thickness of the glove configured to ground a proximity sensor to a finger of the hand.
15. The glove of claim 14, wherein the electrically conductive ink comprises a visibly clear conductive ink.
16. The glove of claim 14 further comprising at least one finger sheath, wherein the electrically conductive ink is disposed near a tip of the at least one finger sheath.
